EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

SHUTTLE FOR WEFT-REPLENISHING LOOMS.

1,074,908.

Specification of Letters Patent.

Patented Oct. 7, 1913.

Continuation of application Serial No. 522,814, filed October 15, 1909. This application filed September 12, 1912. Serial No. 719,956.

To all whom it may concern:

Be it known that I, EDWARD S. STIMPSON, of Hopedale, in the county of Worcester and State of Massachusetts, have invented certain new and useful Improvements in Shuttles for Weft-Replenishing Looms, of which the following is a specification.

The present invention consists in improvements in connection with the weft-carrier holding spring of shuttles used in automatic weft replenishing looms wherein the replenishment of weft is effected by discharging the spent weft-carrier from the shuttle and substituting a fresh one therefor.

These improvements are illustrated in the accompanying drawings, wherein:

Figure 1, is a plan view of the weft-carrier holding end of the shuttle, parts being broken away and shown in section. Fig. 2, is a central vertical longitudinal section. Fig. 3, is a perspective view of the spring. Fig. 4, is a perspective view of the spreader. Fig. 5, is an enlarged plan view of one of the jaws of the spring. Fig. 6, is a vertical section in the plane indicated by the line 6-6, in Fig. 5.

In the drawings, A is the shuttle; B is the weft-carrier holding spring mounted within the shuttle at one end, which will be called the forward end; and C is the guide to direct the incoming fresh shuttle into position between the opposite jaws a, a, of the spring B.

The weft-carrier holding spring B is made of a single piece of high grade annealed cold rolled spring chrome steel. The steel from which the springs are made is of uniform thickness, and the thickness found suitable is nine one-hundredths (.09) of an inch. The metal for the springs is cut from sheet metal plates, preferably being stamped out with suitable dies. It is important that the spring should be cut out in suitable shape. If the spring is of uniform width throughout, it will not possess the necessary resilience at the free ends of the jaws a, if possessing the necessary strength at the places where the greatest strain occurs. To secure the necessary resilience and strength at the different places, the shape and proportions illustrated are employed. The jaws are wider near their free ends, where they grasp the head of the weft-carrier than they are opposite to the bottom of the

incline of the guide C. The outer wide part of the grasping portion of the jaw is sixty-three one-hundredths (.63) of an inch wide. At the narrowest place nearly opposite the bottom of the incline of the guide C, each jaw is fifty-eight one-hundredths (.58) of an inch wide. Between these points the jaw gradually tapers, increasing from its narrowest place toward its free end as shown in Fig. 2. At the place where the shank of the spring comes in contact with the walls of the shuttle it is seventy-seven one-hundredths (.77) of an inch wide. Between the shank and the jaws, the width gradually decreases until the narrowest place is reached. The blank thus cut out of proper shape is bent into the form illustrated in Fig. 3. As here shown the spring comprises the jaws a, a, which grasp the head of the weft-carrier and are separated sufficiently from each other to yieldingly hold the head of the weft-carrier; two curved converging and connecting bows b, b; two substantially parallel legs c, c constituting the doubled shank of the spring, and a curved inner end d uniting the legs c, c. Each of the jaws a is provided on its inner face with vertically extending recesses e which are adapted to coöperate in the usual manner with the usual external projections on the head of the weft-carrier.

The doubled shank is of the maximum width of the spring and bears on its exterior against the walls of the extreme end of the shuttle chamber, as illustrated in Fig. 1, where f indicates one of these walls. This bearing between the shuttle walls and the shank of the shuttle spring B limits the spread of the shank legs. The joining curved bows b, b of the spring B unite the grasping jaws a and the shank legs c, and these intermediate bows b are tapering, as illustrated in Fig. 3, the taper being due to the inclines on the top edge only of the shuttle spring. The spring is narrowed where the bows b, b, merge into the grasping jaws a, a, and the jaws thence widen toward their free ends and on their upper edges only. This construction gives the necessary resilience at the weft-carrier grasping jaws and the required strength where the spring shank bears against the shuttle walls and where it is united to the shuttle.

The shuttle spring B is secured to the shuttle by means of the usual lateral bolt E which extends through the side walls of the shuttle and passes through a hole g in each of the shank legs c. This retaining bolt is held in place in the usual manner.

- Coöperating with the shuttle spring B is the guide C, which is similar to that of United States Letters-Patent to Janelle, No. 10 782,505, February 14, 1905. This guide has the inclined director h which acts to direct the head of the weft-carrier into the space between the jaws a. Integral with the incline h is a top plate i and a bottom plate j. 15 The top plate i extends horizontally over the shank c of the spring B, covering the space between its legs. The outer end of this plate i has a hole through which passes a screw l which enters the body of the shuttle and holds the guide C in place. The bottom plate j rests upon the bottom wall at the end of the shuttle chamber (as shown in Fig. 2) and it underlies not only the shank and bows of the spring but also a portion 20 of the grasping jaws a, by reason of the forwardly extending ears m, m, of the plate j. These ears rest, together with a portion of the side margins of the plate j, on the shoulders n of the recesses provided in the 25 walls of the shuttle for the expansion of the jaws a. The plates i and j are parallel with each other and there is just room enough between them for the maximum height of the shuttle spring B. The space 30 between the two plates i and j is just sufficient to allow the free movement of the jaws a to and from each other and any vertical displacement of the jaws is prevented by the plates.
- 40 A spreader F, is located between the legs c, e to keep the jaws a, a, properly spaced apart. The spreader is forked to straddle the bolt E, and it is maintained in place by the top and bottom plates i and j, of the 45 guide C.
- The weft-carrier holding spring, as thus far described, is an improvement upon the spring of the United States Letters-Patent of Cunniff and Cookson, No. 906,390, of De- 50 cember 8, 1908. The present improved spring has its shank of greater width than the jaws, and the connecting bows vary in width, narrowing gradually from the shank to the jaws, and the jaws widen toward their 55 free ends, thus differing from the spring of Cunniff and Cookson, wherein the spring is of uniform width throughout. By reason of this construction applicant uses the elasticity of the narrowing bows, and the greater 60 width of the shank imparts the necessary strength. The present improved construction reduces to a minimum the breakage of the springs.
- It is customary to provide spreading be- 65 vels on the upper inner edges of the jaws and

above the vertical recesses therein for facilitating the entrance of an incoming fresh weft-carrier and the forcing or spreading apart thereby of the spring jaws. The present invention includes an improvement with respect to these spreading bevels. In accordance with the present invention, each spreading bevel s is doubly inclined. It is inclined inwardly from the top of the jaw downward, as shown in Fig. 6, in the customary manner. In addition, it inclines continuously downwardly from near the free edge of the jaw toward the base thereof, as illustrated in Figs. 3 and 5, in a direction opposite to the inclination of the director h. The result of this double incline, as shown in Fig. 3, is to cause the bevel to grow gradually deeper from front to rear as well as to grow deeper downwardly. The maximum depth is reached in the vicinity of the upper edge of the innermost vertical recess e. From this deepest point the doubly inclined bevel shallows more abruptly toward the rear. The effect of this doubly inclined bevel is to direct the base of a weft-carrier coming in contact therewith toward the inner vertical recess of the jaws, so that the weft-carrier will be held close to the base of the inclined director h. If the shuttle occupies a position toward the outer end of the shuttle box when it receives a fresh weft-carrier, the butt end of the weft-carrier will encounter the inclined director h and thereby direct it so as to be grasped by the inner recesses of the jaws. On the other hand, if the shuttle occupies a position nearer the inner end of the shuttle box when the fresh weft-carrier is received, then the weft-carrier will be directed by the double bevels toward the base of the inclined director h and hence will be grasped by the inner recesses. This is important because the farther away the tip end of the weft-carrier is from the automatically threading eye of the shuttle, the more certainly will the thread be automatically threaded and the thread reels off better from the weft-carrier.

I claim:

1. A loom shuttle having a weft-carrier holding spring composed of a single piece of annealed cold rolled spring chrome steel of uniform thickness bent into shape with a doubled shank for connection with the shuttle, jaws for grasping the weft-carrier, and curved bows connecting the shank and jaws, the shank being wider than any part of the jaws, each curved bow gradually narrowing on its upper edge only from the shank to its jaws, and each jaw increasing in width on its upper edge only toward its free end.
2. A loom shuttle having a weft-carrier holding spring composed of a single piece of spring chrome steel bent into shape with a doubled shank for connection with the shuttle, jaws for grasping the weft-carrier, and

bows connecting the shank and jaws, the shank being wider than any part of the jaws, each bow gradually narrowing on its upper edge only from the shank to its jaw, and 5 each jaw increasing in width toward its free end.

3. A loom shuttle having a weft-carrier holding spring composed of a single piece of spring steel bent into shape with a doubled 10 shank for connection with the shuttle, and jaws for grasping the weft-carrier, the shank being wider than the jaws.

4. A loom shuttle having a weft-carrier holding spring comprising grasping jaws 15 having vertical recesses in their inner faces, and each jaw having on its upper inner edge a spreading bevel above said recesses, said bevel being doubly inclined, that is to say, inclining continuously downwardly from 20 near the free edge of the jaw toward the base thereof until its maximum depth is reached in the vicinity of the upper edge of the innermost vertical recess and also inclining inwardly from the top of the jaw downward; 25 whereby said bevel directs an incoming weft-carrier toward the vertical recesses of its jaw.

5. A loom shuttle having a weft-carrier holding spring comprising grasping jaws having vertical recesses in their inner faces, 30 and each jaw having on its upper inner edge a spreading bevel above said recesses, said bevel being doubly inclined, that is to say, inclining continuously downwardly from 35 near the free edge of the jaw toward the base thereof and also inclining inwardly from the top of the jaw downward.

6. A loom shuttle having a weft-carrier holding spring composed of a shank for connection with the shuttle, jaws for grasping 40 the weft-carrier, and bows connecting the shank and jaws, the shank being wider than any part of the jaws, each bow gradually narrowing on its upper edge only from the 45 shank to its jaw, and each jaw increasing in width toward its free end.

In witness whereof, I have hereunto signed my name in the presence of two subscribing witnesses.

EDWARD S. STIMPSON.
